CLAIM

We claim the ornamental design for a dashboard with graphical user interface, as shown and described.

DESCRIPTION

FIG. 1 is a front view of a dashboard with graphical user interface showing our new design; and,

FIG. 2 is an enlarged view of the portion 2 in FIG. 1.

The evenly-dashed circular broken-line frames enclosing the outer perimeters of the graphical user interface illustrate display screens or portions thereof.

The remaining evenly-dashed broken lines in the drawings depict portions of the dashboard with graphical user interface that form no part of the claimed design.

The dot-dot-dash broken lines encircling portions of the claimed design that are illustrated in enlargements form no part of the claimed design.
